UNITED STATES PATENT OFFICE.

RICHARD L. WILLIAMS, OF BIRMINGHAM, ALABAMA.

DESIGN FOR AN INDICATOR-DIAL.

40,662.

Specification for Design.

Patented Apr. 26, 1910.

Application filed February 24, 1910. Serial No. 545,792. Term of patent 7 years.

To all whom it may concern:

Be it known that I, RICHARD L. WILLIAMS, a citizen of the United States, residing at Birmingham, in the county of Jefferson, State of Alabama, have invented a new, original, and ornamental Design for an Indicator-Dial, of which the following is a specification, reference being had to the accompanying drawing, forming part thereof.

The figure is a plan view of an indicator dial, showing my new design.

I claim:

The ornamental design for an indicator dial, as shown.

RICHARD L. WILLIAMS.
